[57]

CLAIM

The ornamental design for a pouring spout, as shown and described.

DESCRIPTION

FIG. 1 is a top plan view of a pouring spout showing my new design;
FIG. 2 is bottom plan view thereof;
FIG. 3 is a front elevational view thereof;
FIG. 4 is a top plan view of a second embodiment of FIG. 1, the difference residing in the rear support;
FIG. 5 is a rear elevational view of FIG. 4; and
FIG. 6 is a left side elevational view of both FIG. 1 and FIG. 4, the right side being a mirror image.

FIG. 1

FIG. 2

FIG. 3

FIG. 4

FIG. 5

FIG. 6
